UNITED STATES PATENT OFFICE.

HARRY F. NILES, OF CHICAGO, ILLINOIS, ASSIGNOR OF ONE-THIRD TO ERVA A. SCHLICK, OF CHICAGO, ILLINOIS.

VALVE.

1,282,918.

Specification of Letters Patent. Patented Oct. 29, 1918.

Application filed January 22, 1918. Serial No. 213,193.

To all whom it may concern:

Be it known that I, HARRY F. NILES, a citizen of the United States, residing at Chicago, in the county of Cook and State of Illinois, have invented certain new and useful Improvements in Valves, of which the following is a specification.

My invention relates to improvements in valves.

10 One of the objects of my invention is to provide a puppet valve that is self adjustable on its seat.

Another object of my invention is to provide a valve of this character that is self cleaning when laterally displaced on its seat by ordinary conditions of operation, and another object is to provide in a valve a larger available seating surface than that of the port which the valve opens and

20 closes.

Another object is to provide a valve that is not held in rigid alinement with its port seat.

Other and further objects of my invention 25 will become readily apparent to persons skilled in the art, from a consideration of the following description when taken in conjunction with the accompanying drawings, wherein—

30 Figure 1 is a central section of a valve part of a conduit and valve operating mechanism.

Fig. 2 is a section taken on line 2—2 of Fig. 1.

35 In both views the same reference characters are employed to indicate similar parts.

Valves of the puppet type consist, generally, of a disk having an angularly disposed rim affording a seating surface, in co-40 action with a similar surface surrounding a port adapted to be closed and opened by the valve. Such valves are provided with a centrally positioned stem perpendicular to the face of the disk and this stem is guided 45 by means that permits free vertical movement of the valve but which holds the valve otherwise in rigid relation with its port. Any lateral displacement of the stem, due to wear of the stem or its guides, permits 50 the valve to cock up on one edge of its seat, leaving large free surfaces of the seats, of the valve and port, for deposit of carbon, thus preventing effective closing of the port and causing loss of compression in the cylinders of the engine.

55 In my improved valve I make the seat-

ing side of the disk a segment of a globe and from the same radial point, or globe axis, I describe a globular surface upon which is seated, and around which is movable the guide for the valve stem.

In the disclosure of my invention I have shown a conventional structure in which 5 is a frame containing a conduit or gas passage 6, inclosed by the wall 7. In the wall 65 is a valve port 8 having a valve seating surface curved to conform with the seating surface of the valve. The valve 9 has a seating surface 10 conforming in outlines with that of a globe; the axis of which is 70 the point 11. The curve of the valve seat and the port seat are struck from the axial point 11 on a radius shown by the broken line 12.

The stem 13, of the valve, is not rigidly 75 guided and permitted to move only in a vertical plane, as in the usual practice. The stem is surrounded by a sleeve 14, having a laterally extending rim 15 which has a concave face 16. The face 16 is seated on 80 a convex surface provided on the confronting surface of the wall indicated by 17. These surfaces are struck on a radius shown by the broken line 18 projected from the point 11. Now it is evident that when the 85 lower end of the stem is moved in a lateral direction that the valve 9 will not leave its seat, although there may be a change in the contacting surfaces. While this movement may occur the rim 15 will be moved 90 on its confronting surface without being moved axially.

An open spiral spring 19 surrounds the stem 13 and the sleeve 14 with one end bearing against the rim 15 and the other 95 end against a washer 20 that affords an abutment for the other end of the spring is held in place by a pin 21. The spring 100 yieldingly holds the valve closed and holds the flange 15 on its seat. The lower end of the stem 13 is convexed, as at 22.

A valve moving stem 23 is arranged axially with the valve stem 13 and has its confronting end concaved as at 24 to bring the two stems in true alinement when the 105 valve is being opened. A cam is shown in dotted lines for opening the valve.

Where valve stems are rigidly held in guides, against lateral displacement, and the valve is of the usual type heretofore 110 pointed out, the operation of the cam and the spring tend to produce wear on the

- guides and on the stem by enlarging the former and reducing the latter, permitting the cocking of the valve and the resulting leak.
- 5 If the lower end of the valve stem 13 should perchance be out of vertical alinement, the valve will properly seat, and the valve lifter 23 will bring it back into alinement as a result of the concaved and convex confronting ends of the respective stems.
- 10

While I have herein shown and described a single embodiment of my invention for purposes of complete disclosure, it is manifest that changes in the configuration and disposition of the parts may be made within the scope of the appended claims.

Having described my invention, what I claim is:

- 20 1. The combination of a valve supporting frame having a valve port, the walls of which are transversely curved to provide a seat to receive a spheroidal valve; a spheroidal valve for coöperation with said seat, having a stem; a stem guide adapted to permit lateral movement of said stem and axially disposed means to open and close the valve.
- 25 2. The combination of a valve supporting frame having a valve port, the walls

of which are transversely curved to provide a seat to receive a spheroidal valve; a spheroidal valve for coöperation with said seat; a stem vertically depending from said valve; a stem guide adapted to permit lateral movement of the valve; a spring to close the valve; a valve lifter and means co-operating with said stem and lifter to return the stem to position of vertical alinement before being lifted.

3. The combination with a valve supporting frame having a surface for a valve-stem guide curved from a given point in the axial line of the valve stem; a valve and its seat spaced away from said surface, said valve having its seating surface curved from the same given point; a valve stem extending from the valve and through said first-mentioned surface; a valve-stem guide surrounding said stem and seated on said first-mentioned surface; and a spring yieldingly to resist opening of said valve and holding said valve and said guide on their respective seats whereby said valve stem may be moved laterally without causing the valve to leave its seat at any point.

In testimony whereof I hereunto set my hand.

HARRY F. NILES.
